UNITED STATES PATENT OFFICE.

SAMUEL TURNER AND THOMAS EASTAUGH, OF SPOTLAND, ROCHDALE, ENGLAND, AS
SIGNORS TO SAMUEL TURNER & COMPANY, LIMITED, OF SPOTLAND, ROCHDALE,
ENGLAND.

LOOM FOR WEAVING.

Application filed September 26, 1928, Serial No. 308,394, and in Great Britain July 2, 1927.

This invention relates to looms for weaving with more particular reference to those which are fitted with automatic weft replenishing mechanism, and has for its object 5 to devise improvements in the construction and arrangement of such mechanisms which will enable fine quality fabrics to be woven upon such looms.

The invention consists in the provision of 10 means for preventing what is known as a "double pick," that is the carrying into the shed of any loose weft ends that may be left from a discharged cop or cut from the cloth selvedge.

15 The accompanying drawings illustrate one mode of carrying out the invention:—

Figure 1 is a more or less diagrammatic plan showing a part of the breast beam of a loom and sley with parts mounted and arranged thereon in accordance with the invention;

Figure 2 is an elevation of the end of the sley at the transfer end of the loom, and

20 Figures 3 and 4 are two views illustrating 25 a detail.

In carrying our invention into effect we may apply our improvements to existing looms or to looms specially built for the purpose, and such looms are provided with 30 the usual accessories incidental to weft replenishing looms, that is to say, with some form of magazine (not shown) for the cops and with a transfferer *a* on a hammer shaft *b* for the purpose of pushing a full cop into 35 the shuttle and simultaneously ejecting therefrom the empty cop whenever the weft requires replenishing.

We also provide the usual weft fork and hammer mechanism (not shown) for bringing 40 into operation the weft replenishing means such as is commonly employed on automatic weft replenishing looms.

45 For the purpose of cutting the tag ends of the cloth selvedge we provide a suitable cramp and scissors mechanism and in order to dispose effectively of the weft ends cut off by the scissors, we arrange the weft to pass from the shuttle under or round a stationary hook member *c* (Figure 1) and adjacent to said hook member we provide a

toothed quadrant arm *c*² mounted on a bracket *c*³ on the transfer shaft *k* and operated by a bunter *c*⁶ on the sley. The bunter *c*⁶ contacts with the roller or projection *c*⁵ on the arm *c*² when the transfer shaft 55 *k* is rotated during operation of the weft replenishing mechanism so as to move the arm against its controlling spring *c*⁴ and thus clear away any loose weft ends that might otherwise interfere with the weaving 60 operation.

Furthermore, for the purpose of preventing what has hitherto been a considerable difficulty in connection with weft replenishing looms, namely, the possibility of a double pick or the carrying into the shed of loose weft ends left after discharge of the pirn from the shuttle box we arrange the 65 checking straps at the back of the sley or provide an iron rod or Bowden wire *u* (Figure 1) fixed behind the hand-rail containing leather tag ends *u*¹ which work in the same way as the check strap usually arranged in the front of the sley, and in this way we are 70 enabled to form a slot or opening *u*² (Figure 75 2) in the sley block, and in a suitable position upon the loom frame we arrange a stationary hook *u*³, brush, or like contrivance which may or may not be spring controlled and which, as the sley moves forward, enters 80 the hole therein and lays hold of any loose end of weft so as to draw the same away from the cloth and prevent the weft end from being carried into the shed.

Moreover, we prefer also to provide a pirn 85 chute *w*¹ (Figure 2) beneath the shuttle box which makes it possible for the pirns to drop straight down into the empty pirn can so that there will be no fear of the pirns rebounding in such a manner as might otherwise 90 prevent the shuttle from being discharged from the shuttle box. Such chute may also have a leather or like guide or buffer *w*² to assist in guiding the pirn into 95 the pirn can.

It will be understood that the invention is not to be limited to the foregoing details of construction which are given by way of example only, nor is it to be limited to any particular type or construction of weft re- 100

plenishing loom to which it is to be applied.

Having now described our invention, what we claim as new and desire to secure by Letters Patent is:-

- 5 In an automatic weft replenishing loom, a transfer shaft, a weft end catcher supported by the transfer shaft and including a pivoted hook member, a spring for normally holding said member in one position,

a sley, a bunter on said sley, and means on 10 said hook member adapted to be engaged by said bunter during weft replenishment to rock said hook member to weft engaging position.

In testimony whereof we have signed our 15 names to this specification.

SAMUEL TURNER.

THOMAS EASTAUGH.
